LAMP SHADE

Charles T. Brady, Detroit, Mich.

Application February 1, 1930. Serial No. 425,164

1 Claim. (Cl. 240—1.1)

The present invention pertains to a novel lamp shade, and the principal object is to provide a device of this character having the outward appearance of an ornamental shade for decorative purposes and at the same time equipped with a lens which imparts a daylight character to the light emitted from the shade. The invention provides an efficient construction which restricts the emitted light to the modifying lens, although the material which forms the housing of the shade may be translucent in order to take on a glowing appearance when the lamp therein is supplied with current.

Another feature of the invention is the provision of a reflector supported by the lamp within the shade and directed towards the lens to increase the quantity of light shed thereon.

The invention is fully disclosed by way of example in the following description and in the accompanying drawing, in which—

Figure 1 is a vertical section of a lamp shade constructed according to the invention;

Fig. 2 is a fragmentary plan view thereof;

Fig. 3 is a fragmentary bottom plan view;

Fig. 4 is a perspective view of the lens holder with the lens therein; and

Fig. 5 is a detail section of a modified construction.

Reference to these views will now be made by use of like characters which are employed to designate corresponding parts throughout.

The principal embodiment of the lamp shade is constructed on a skeleton framework which includes an upper ring 1 and a larger lower ring 2 spanned by curved ribs 3 welded or otherwise secured thereto to form a somewhat conical structure. The lower ends of the ribs are bent down vertically at 4 and surrounded by another ring 5 secured thereto and having substantially the same size as the ring 2, beneath which it is positioned. The top structure consists of rods 6 secured to the ring 1 and extending inwardly therefrom for the purpose of supporting an internally threaded ring 7, concentric with the ring 1, for a purpose which will presently appear.

Another set of rods 8 extend inwardly and upwardly from the lowermost ring 5 to which they are secured. To the free ends of these rods is secured another ring 9 to which in turn are attached angular fingers 10 for a purpose which will presently be described. This construction is made more secure by another ring 11 secured to and enclosed by the fingers 10 and also secured to the rods 8.

The framework is covered with a suitable ma-

terial 12, such as parchment or silk, extending from the upper ring 1 over the rings 2 and 5 to the ring 9 to which it is attached. A suitable trimming material 13 may be employed to bridge the space between the rings 9 and 11, and other trimming may be used on other parts of the covering material 12 which may consist of one or more pieces as desired.

The object of the fingers 10 is to support a lens holder in the nature of a ring or collar 14 having bayonet slots 15. These slots are arranged to register with the fingers 10, whereby the holder may be supported by these fingers when received in the slots as shown in Figures 1 and 4. The lower end of the holder is flanged inwardly at 14' to support a plano-convex lens 16 having its convex side exposed and its plane side covered with a bluish flat lens or disk 17. This member is held in firm contact with the lens 16 by a split ring 18 sprung into the holder 14 above the member 18.

The shape and position of the lens 16 are such that the light passed therethrough is condensed into a smaller area and thus increased in intensity. The ring 7 threads on a conventional 80 socket 19 into which is screwed an electric lamp or bulb 20. In order to prevent the waste of light through the open upper end of the shade and to divert the light at this end into the lens 16 and 17, there is provided a reflector in the 85 nature of an apertured disk 21 enclosing the neck of the lamp 20. The disk is frictionally supported in the position indicated by its engagement with the downwardly flared wall of the lamp 20 received in the aperture. The disk is 90 further formed with a number of smaller apertures or perforations 22 for ventilation. The device is assembled by first attaching the shade alone to the socket 19, then screwing in the lamp 20 with the reflector 21 mounted thereon, and 95 finally mounting the lens holder 14 on the fingers 10. The exposed ends of the fingers 10 are bent back at 10' so that the sharp extremities will not be exposed to scratch the hands of the user assembling the device while screwing the bulb 20 100 into the socket 19.

In Figure 5 is illustrated a modified construction wherein the support for the lens holder consists of a threaded ring or collar 25 suitably attached to the innermost ring 11'. The lens holder is also a threaded collar 26 receivable in the ring 25 and having its lower edge flanged inwardly at 27 to retain a planoconvex lens 28. The lens is held firmly against the flange 27 by a split ring 29 sprung into the holder 26.

The lens 28 is also designed to impart a bluish or daylight character to the light passing therethrough but consists of a single piece of glass for this purpose as distinguished from the two lenses used in Figure 1. The lens 28, instead of being colorless like the lens 16, has the necessary quantity of bluish coloring matter diffused therethrough either homogeneously or by diffusing of a bluish flat lens to the plane side thereof.

10 Although specific embodiments of the invention have been illustrated and described, it will be understood that various alterations in the details of construction may be made without departing from the scope of the invention, as indicated by the appended claim.

15

What I claim is:—

An ornamental lamp shade comprising a wire frame including three ring members mounted in parallel relation, two of said ring members defining respectively the top and bottom of the shade, and the third ring member defining an aperture spaced inwardly from said bottom ring member, and between the top and bottom ring members, a translucent covering extending between said top ring member and said bottom ring member and between said bottom ring member and said third ring member, and a lens removably mounted in said third ring member.
